(57) **CLAIM**

The ornamental design for a guitar stand, as shown and described.

DESCRIPTION

FIG. 1 is a front elevation view of a guitar stand showing my new design;

FIG. 2 is a left side elevation view;

FIG. 3 is a right side elevation view;

FIG. 4 is a top plan view;

FIG. 5 is a bottom plan view;

FIG. 6 is a rear elevation view; and,

FIG. 7 is a perspective view thereof shown with environment. The broken lines showing a guitar in FIG. 7 are for the purposes of illustrating the environment of the article only and form no part of the claimed design.
